LINE-COMPOSING AND CASTING MACHINES

Karl Debus, Bad Homburg V. D. H., and Kurt Heimel, Frankfurt am Main, Germany, assignors to Linotype Gesellschaft mit beschränkter Haftung, Berlin-Tempelhof, Germany

Application February 7, 1956, Serial No. 564,077

Claims priority, application Germany February 8, 1955

1 Claim. (Cl. 199—45)

The invention relates to a mechanism for changing over magazines in line-composing and casting machines, particularly machines having a plurality of distributors and pivoted magazines, the position of which can only be varied in relation to the assembling mechanism.

In the machines of this type hitherto known, changing over of the magazine was affected mechanically by means of a hand lever or a hand wheel through intermediate members. The main disadvantages of this method are that the compositor has to leave the keyboard to perform the operation which takes a substantial amount of force, and a comparatively long time. A serious disadvantage with known changeover mechanisms which are mechanically operated is that they are unsuitable for line-composing and casting machines which are controlled by means of perforated strips.

According to the present invention, all these disadvantages are overcome as a result of the fact that the power necessary for changing over the magazine is supplied by an electro-magnetic system which is actuated by hand or by means of a relay which may, if necessary, be controlled by the perforated strip.

In one embodiment of the invention, the changeover may be effected in such a manner that the member of the electro-magnetic system providing the mechanical power acts directly on the frame supporting the magazine. In this case, either a double electro-magnet is used, that is, an electro-magnet which acts mechanically in both directions, or a simple solenoid which is permanently energized in at least one working position and is de-energized for the other working position. Instead of an ordinary solenoid, a self-locking solenoid is also possible, which is mechanically locked in the working position and de-energized.

This direct-acting mechanical embodiment has the advantage for example, that additional mechanical transmission members are not needed. In certain line-composing and casting machine systems, however, it is necessary, before changing the position of the magazine, to displace other machine parts, for example matrix escapement bars, so as to open the way for the magazine; the escapement bars are returned when the final magazine position has been reached.

For such types of machine it is a greater advantage if the member of the electro-magnetic system supplying the mechanical power according to the invention is coupled to an intermediate member, for example a shaft which both controls the matrix escapement bars and actuates the actual magazine.

In this case it is an advantage to use as a magnet a simple solenoid which needs only a brief current impulse for each operation, which impulse is initiated by means of a manually operated member for example a key, or by means of relays controlled by perforated strips.

This embodiment with actuation by means of a relay or set of relays controlled by a perforated strip has the

2

further advantage that only a single combination of holes is necessary.

The mechanism according to the invention is particularly advantageous when the mechanical member of the electro-magnetic system acts on a control member such as a cam plate during the first working stroke in such a manner that turning of the shaft takes place in one direction and after the solenoid has been de-energized, for example as a result of releasing the manually operated key, the push rod which has been moved back, for example by its own weight, is guided in such a manner that it reaches a starting position which causes a rotation of the magazine-changing shaft in the opposite direction during the next working stroke.

15 The displacement of the actual magazine may conveniently be effected by means of a second cam which is provided on the magazine-changing shaft and which causes the magazine movements through a follower provided on the magazine supporting frame. Yet a third cam may conveniently be mounted on the same shaft, by means of which the matrix-escapement bars are moved, for example through a follower and lever.

20 A specific embodiment of the invention will now be described by way of example, with reference to the accompanying drawings.

Figure 1 shows diagrammatically on a reduced scale the changeover arrangement according to the invention in which the lower magazine A of the machine is in the working position.

25 Figure 2 is the same view in the operating position in which the upper magazine B is in the working position. The magazines A and B and the escapement bars are indicated in both figures by lighter outlines.

30 The dash-lines in both figures indicate the position of the push rod at the moment when the rotation of the magazine-changing shaft is completed.

35 The dash-lines in both figures indicate the position of the push rod at the moment when the rotation of the magazine-changing shaft is completed.

The electro-magnet 1 is supplied through the lines 2, 3 and the manually operated key 4 which may be replaced by a relay or a set of relays in the machine controlled by a perforated strip, with current from the source 5. The armature 6, for example an ordinary plunger of the electro-magnet 1, is connected by means of a number of intermediate members 4 to 14 to the cam plates 15 and 18. More in detail, armature 6 is connected by means of the articulation 7 to the push rod 8, at the other end of which is mounted a pin 9 which is movable in the cam-slot or cam member 10 of the control member or cam-plate 11. At each end the cam-slot has recesses 13 and 14 respectively, which effect a more reliable coupling of the push rod 8 to the cam-plate 11 through the pin 9 during the changeover.

40 45 50 55 The cam-plate 11 is rigidly mounted on the magazine-changing shaft 12, on which is also mounted the cam-plate 15 which moves the matrix-escapement bars 21 through a follower 16 and a spring-loaded lever 17.

Also mounted on the magazine-changing shaft 12 is the cam-plate 18 which effects the movement of the magazine through the follower 20 fixed to the lower magazine supporting frame 19.

60 The mechanism according to the invention operates as follows:

In order to change over from one magazine to the other, the manually operated key 4 (Figure 1) is briefly depressed and released again. The electro-magnet 1 thus receives an impulse as a result of which its armature 6 executes a movement in the direction of the magazine-changing shaft 12. This power stroke is transmitted through the push rod 8 and the pin 9 to the recess 13 of the cam-slot in cam plate 11 so that the cam-plate 11 is turned in clockwise direction at the same time turning the magazine-changing shaft 12.

With the turning of the shaft 12, the cam-plate 15 is likewise turned in a clockwise direction, as a result of which the matrix-escapement bars 21 are lifted from their operating position through the follower 16 and the lever 17 and are moved in such a manner that the motion of both magazines can no longer be obstructed by the matrix escapement bars 21.

In addition, the cam plate 18 is turned in the same direction, as a result of which the frame 19 carrying the magazines is moved by means of the follower 20 in such a manner that a changeover is effected from the magazine A which was previously in the operating position, to the upper magazine B so that the latter is brought into the operating position. The corresponding outermost or highest position of the push rod 8 can be seen in light 15 dash-lines in Figure 2.

The solenoid, which has been de-energised in the meantime, then permits the armature 6 and the push rod 8 to return to the lower dead-centre position by gravity, the push rod 8 being transferred by the pin 9 through the 20 cam-slot in cam plate 11 from the position illustrated in broken lines in Figure 2 to the position shown in full lines in that figure, preparation thus being made for the next change.

The mechanism is now ready, on actuation of the key 4, to act in such a manner that the magazine-changing shaft 12 is turned in the opposite direction so that the first magazine A is again brought into the working position.

We claim:

In a line-composing and casting machine having a plurality of magazines, a magazine changeover device comprising an electromagnet having a movable armature, a pushrod coupled to said armature, a mechanism for moving a selected magazine to an operative position, which mechanism has an operating shaft, a cam plate secured to said shaft, the cam plate comprising a cam member shaped and arranged to cooperate with said pushrod so that a rotation of said shaft takes place in one direction on movement of the armature effected by energization of the electromagnet and, after the electromagnet has been deenergized, said push rod is guided by said cam member to such a position that rotation of said shaft in the opposite direction is effected during the next working stroke.
